POWER OUTLET RECEPTACLE

Walt W. Bundy, Benning Park, Columbus, Ga.

Application November 28, 1945, Serial No. 631,456

1 Claim. (Cl. 173—330)

(Granted under the act of March 3, 1883, as
amended April 30, 1928; 370 O. G. 757)

1

The invention described herein may be manufactured and used by or for the Government for governmental purposes, without the payment of any royalty thereon.

This invention relates in general to power outlets and more particularly to devices for rapidly and easily providing a power outlet receptacle at any desired location on a power cable.

In temporary installations where portable power units are utilized, it is sometimes desirable to provide a power outlet receptacle at an intermediate point of the power cable so that additional power outlets may be made available from the cable if desired. Such outlets must of necessity be rugged and of simple construction.

It is an object of my invention to provide a device which may be easily and rapidly applied to a power cable to form a power outlet receptacle.

It is a further object of my invention to provide a power outlet receptacle that may be rapidly mounted on a power cable to provide a strong weatherproof connection where desired.

The above and other objects and advantages will become readily apparent when the following specification is read in conjunction with the accompanying drawings in which:

Figure 1 is a vertical cross-sectional view of one embodiment of my invention mounted on a power cable taken along the plane A—A of Figure 3.

Figure 2 is a top view of the device shown in Figure 1; and Figure 3 is a side view of the device shown in Figure 1 and Figure 2.

Referring to Figure 1, it is seen that the reference numeral 10 refers to a jacket element made of insulating material, preferably molded rubber, having a cross section of oval configuration and having two tail portions 11 and 12 which are intended to be wrapped around a cable 13 in an overlapping manner. Rubber cement may be applied to the inside surface of the overlapping tail portions 11 and 12 and covered with cloth which may be stripped off when desired so as to cement the complete unit to the cable 13 and the overlapping portions 11 and 12 to each other.

Two elongated contact members 14 and 15, made of electrical conducting material such as spring brass or the like have mounted thereon in spaced relationship a spring clip 14a and 15a respectively arranged to form a jack to receive

2

and hold the prongs of an electric plug. The lower end of each of the contact elements 14 and 15 is provided with a hook 16 and 17 respectively, which faces outwardly to facilitate the soldering of each hook to a wire of the electric power cable which it is desired to tap.

Referring to Figure 2, the reference numeral 18 refers to a tongue shaped element made of molded rubber or other suitable electrical insulating material to be placed between the two wires of the cable 13 in order to separate and electrically insulate the wires of the cable from each other. The tongue shaped element 18 also serves to separate and insulate the jack elements 14 and 15 from each other, and, together with the outer jacket portion 10, serves to form a cavity into which the jack elements 14 and 15 fit, holding them in the proper relationship to receive the prongs of an electric plug.

20 A circular cover element 19 formed of electrical insulating material and having two openings 20 and 21 therein is securely held in a round opening on the top side of the jacket element 10. The openings 20 and 21 are aligned with the jack elements 14 and 15 respectively to enable the prongs of a plug to be inserted into the jack.

25 In installing the device in a power cable, it is necessary that the cable be split with a sharp instrument for a length of a few inches, the cable wires cleaned adjacent to each other and the hooks 16 and 17 on the lower ends of the jack elements 14 and 15, respectively, soldered to the cable wires. The outer jacket 10 is then fitted around the cable with the tongue 18 inserted between the two cable wires. The jack elements 30 14 and 15 are placed in the cavity provided for them and the rubber cement on the overlapping tail portions 11 and 12 is uncovered by removing the cloth covering and the tail portions 11 and 12 wrapped tightly around the cable and pressed firmly into place. The outlet is now ready for use and provides a sturdy weatherproof outlet, which may be placed at any desired intermediate portion of the power line.

35 Although I have disclosed and described one embodiment of my invention, it is obvious that many changes may be made in my device without departing from the spirit of the invention as set forth in the appended claim.

I claim:
50 In a device for providing a power outlet recep-

tacle between the ends of a power cable, the combination comprising an outer jacket of resilient insulating material and having two tail portions, a vertically disposed separating member provided in said jacket, a jack member on either side of said separating member, curved means on the lower end of each of said jack members for connection to the conductors of said power cable, said tail portions being folded in across the axis of said receptacle at the opposite side of the 10 cable from the receptacle cavity.
